UNITED STATES PATENT OFFICE.

ALFRED WEED, OF PHILADELPHIA, PENNSYLVANIA.

MACHINE FOR GRINDING AND DRESSING FILE-BLANKS.

SPECIFICATION forming part of Letters Patent No. 287,746, dated October 30, 1883.

Application filed January 20, 1883. (No model.)

To all whom it may concern:

Be it known that I, ALFRED WEED, of the city and county of Philadelphia, in the State of Pennsylvania, have invented certain new and useful Improvements in Machines for Grinding and Dressing File-Blanks; and I do hereby declare the following is a specification of my improvements, reference being had to the accompanying drawings, wherein—

10 Figure 1 is a front view of the machine in perspective, showing the general distribution of parts. Figs. 2 and 3 are respectively front and rear elevations thereof. Fig. 4 is a longitudinal vertical section on the line xx of Fig. 12; and Fig. 5 is a vertical longitudinal section, on an enlarged scale, through the center of the grindstone-shaft, showing certain details of the adjusting mechanism.

15 My invention consists in a machine whereby a number of file-blanks may be ground or dressed at once, the movements being, as far as possible, automatic, and the working parts being so constructed and combined as to permit the placing of the blanks in position, their examination during the grinding, and their removal when finished, without interrupting the movements of the machine. Furthermore, since to insure uniformity and accuracy in the blanks it is essential that the movements of 20 the working parts should be true, my invention further consists in means whereby all these parts can be readily and minutely adjusted. I also provide a device for dressing and truing the face of the grindstone.

25 To facilitate comprehension of the more detailed description hereinafter given, the main features of the machine may be pointed out by reference to the perspective view shown in Fig. 1.

30 A frame, F' , in which the blanks (indicated by dotted lines) are held is vertically reciprocated in a direction tangential to the periphery of the revolving grindstone C' . This reciprocation is effected by screw-and-bevel gear-

35 ing above the frame, actuated alternately in opposite directions by belts automatically shifted upon the pulley G . The grindstone is also reciprocated continuously in the direction of its axis of rotation and across the face of the frame F' . The bearings of the grindstone-shaft are adjustable toward and from the frame F' , and the latter is held against the grinding-

face by rollers P , which are also separately adjustable, all these adjustments being effected by means of a single hand-wheel, M . The device C^2 for dressing the grindstone face is vertically adjustable toward the surface of the stone, and can also be drawn laterally across it. 55

The following is a description of the various details: The frame A of the machine rests upon base-girders B , which are secured together by end plates, B' . A bridge, B^2 , braces the upper ends of the frame A , and supports the mechanism by which the file-blank frame is reciprocated. D^2 are pillow-blocks forming bearings for the grindstone-shaft D , which is driven by the pulleys $C C'$. The grindstone C' is secured in position between the disks C^3 , one of which is rigidly attached to the shaft D , and the other is adapted to move thereon, being clamped against the stone by means of nut N working upon a threaded portion of the shaft. One end of the shaft D has a cam-slot, D^2 , formed on it, and a pin, D^3 , in the eye-piece D^4 , secured to the pillow-block D' , fits in the cam-slot D^2 , and causes the shaft D , carrying the grindstone, to reciprocate laterally during its revolution. The pillow-blocks D^2 slide upon the girders B , their movements being controlled by the screw-rods O , which, together 65 with their adjacent mechanism, are shown on an enlarged scale in Fig. 5. The screws O engage with sleeve-nuts O' , revolving in suitable bearings in the frame A , and secured against longitudinal movement by collars O^2 70 and M' . The collars M' are provided with miter-gears, as shown, which engage with corresponding miter-gears, M^2 , upon the shaft m , mounted in projecting bearing-pieces L , and actuated by means of the hand-wheel M , and 75 as the screw O and its nut O' , on one side of the machine, are threaded in the reverse direction from that of the similar screw and nut on the opposite side, it is obvious that the rotation of the hand-wheel M in either direction will shift both the pillow-blocks D^2 80 together toward or from the frame A . A cross-head, F^4 , is adapted to move vertically in guides F^4 within the frame A . The cross-head is cast with a central enlargement or 85 socket to receive the end of the actuating-screw held securely in position by means of the pin F^4 , which passes through both the cross-head and screw. Beneath this socket, 90

95

100

and at right angles to the cross-head F^3 , is the transverse extension b , longitudinally slotted, as shown at a in Fig. 4, to receive the carriage F^{16} , the cross-section of the slot and of the carriage F^{16} being indicated by the dotted lines in Fig. 3. A screw, F^{15} , extends from end to end of the slot, passing through a correspondingly-threaded opening in the carriage F^{16} . It will thus be seen that while the carriage F^{16} 5 may be adjusted at any point in the length of the slot by turning the screw F^{15} , its weight does not rest upon said screw, but is sustained by the inclined sides of the slot a . The carriage F^{16} is provided with two pendent lugs 10 upon its under face, bored out for the reception of a bolt, F^{18} , which passes through the eye of the suspension-rod F^2 . The open rectangular frame F' is secured to the lower end of the rod F^2 by means of the screw-thread 15 and the jam-nut F^{19} . Within the rim or flange 20 formed by the sides of the frame F' is snugly fitted the plate F , secured in position by means of the bolt and latch $f^3 f^4$, which hold it against the diagonal projections across the 25 corners of the frame. The plate F is provided on the side adjacent to the grindstone with parallel cross-pieces f' , forming rests for the file-blanks f , the tangs of the latter being inserted behind a cross-piece, f^5 , at the bottom 30 of the plate F . Rollers $P P$, journaled upon carriages $Q Q$, are arranged to bear against the back of the frame F^2 , (or that side which is farthest from the grindstone,) but clear of the plate F , so as not to interfere with its removal 35 at any time from the frame F^2 . The carriages $Q Q$ slide in horizontal dovetailed guides $K K$ on the main frame A , each carriage being formed with an inside thread engaging with a screw, P' , and the screws $P' P'$, 40 whose threads run in opposite directions, being actuated by means of the miter-gears M^3 , M^4 , and M^5 , M^6 , respectively. The miter-gears M^4 and M^5 are mounted upon the shaft m , already referred to, and by the rotation of 45 the hand-wheel M can be adjusted toward or from the frame F^2 , thus causing the blanks supported on the plate F to bear more or less closely against the face of the grindstone C . Each of the miter-gears M^1 , M^2 , M^3 , M^4 , M^5 , M^6 , 50 M^7 , and M^8 is secured to its shaft by a set-screw, as indicated, by loosening which the gear is released and the shaft remains stationary, while the others are revolved. This enables the operator to readily correct any 55 want of parallelism in the adjustable carriages $Q Q$ or pillow-blocks $D' D'$ by loosening the gear, which may be too far back, and rotating the other until the proper point is reached for causing it to again engage with its shaft. 60 So, also, the pillow-blocks may both be moved simultaneously without affecting the position of the rollers, and vice versa.

The devices for causing the vertical reciprocation of the frame F' are as follows: A screw, F^5 , is secured to the movable cross-head F^3 , and engages with a nut bevel-gear, F^6 , revolving horizontally in bearings upon the

bridge B^2 . A corresponding bevel pinion, F^7 , meshing with the gear F^6 , is secured to the horizontal driving-shaft H , mounted in bearings $I I$, and provided with two loose pulleys, $G^1 G^2$, and an intermediate fast pulley, G . Standards $J J$ upon the bridge B^2 support the sliding bars E^6 and E^7 , the former of which carries the belt-shifters $E^9 E^9$, and the latter 70 the similar belt-shifters, $E^8 E^8$. The bars E^6 and E^7 are movable independently of one another, but that end of the bar E^7 which carries the belt-shifters E^8 abuts against the projecting side of the belt-shifter E^6 , so that when the bars are in the position shown in Fig. 3 the movement of the bar E^7 to the left, or toward the central pulley, G , will push the belt-shifters E^9 and bar E^6 toward the loose pulley G^1 . Conversely, when the belt-shifters E^9 are upon the loose pulley G^1 and the belt-shifters E^8 are 75 upon the central pulley, G , the movement of the bar E^6 and its belt-shifters E^9 to the right, or toward the central pulley, G , will push the bar E^7 and belt-shifters E^8 toward the loose pulley G^2 . It will be observed, however, that 80 this combined or joint movement of the bars only takes place when the belt-shifters are upon immediately adjacent pulleys, and then is only effected through the movement of the bar whose belt-shifters are for the time being upon a loose pulley. Thus, supposing the bars to be 85 in the positions shown in Fig. 3, if the bar E^7 (whose belt-shifters E^9 are then upon the fast pulley G) should be moved to the left, or toward the loose pulley G^1 , the bar E^6 will remain 90 stationary, the belt-shifters will be in the positions shown in Fig. 2, and then neither bar will by its movement affect the other. Connecting-rods $E^4 E^5$ are respectively secured to 95 the bars E^6 and E^7 by clamps E^2 and E^3 . The connecting-rod E^4 is actuated through the bell-crank E , and the rod E^5 through a similar bell-crank, E' . The shafts or pivots of these bell-cranks extend across the under side of the bridge B^2 , as shown in Fig. 4, so that the upright arms of the bell-cranks are upon the same side thereof as are the sliding bars, while the horizontal arms are on the opposite side. 100 Pieces $F^{10} F^{10}$ are mounted, one upon a horizontal arm projecting from the top of the screw F^5 , and the other upon the sliding cross-head F^3 , carrying the bar F^9 , upon which the tap-pins F^8 and F^{12} are supported in vertically adjustable clamps. The pieces $F^{10} F^{10}$ are tapped with 105 a number of screw-holes, so as to permit the lateral shifting of the bar F^9 .

The construction of the grindstone-dressing devices is as follows: A horizontal shaft, A^3 , having at one end a cross-handle, A^4 , is freely suspended in bearings $A^2 A^2$, which slide vertically in ways $A' A'$, cast upon the side of the frame A , adjacent to the grindstone C . The sliding bearing-pieces $A^2 A^2$ are centrally threaded to engage with the vertical screws $A^5 A^5$, provided with miter-gears A^6 , which are actuated by means of the pinion-shaft A^8 and hand-wheel A^7 . As the screws $A^5 A^5$ are 110 threaded in opposite directions, the rotation 115

of the hand-wheel A⁷ moves the bearing-pieces A² simultaneously in the same direction. The operator is thus enabled to impart a slow upward or downward motion to the shaft A³, 5 moving it toward or from the grindstone. The gears A⁶ being secured to their respective shafts by set-screws, (similar to those already described in reference to the gears M', M', &c.,) parallelism of the shaft A³ with the grindstone- 10 face can be insured. Secured between collars clamped upon the shaft A³ are several toothed dressing-disks, C².

The mode of operation of the machine is as follows: Should the grindstone require to have 15 its surface trued, power is applied to its driving-pulley C, and when the stone is in rapid rotation the hand-wheel A⁷ is turned so as to adjust the dresser-shaft A³ toward it. When the toothed disks C² have been brought into 20 contact with the face of the stone, they are drawn back and forth across it by means of the handle A⁴ until the stone is cut or dressed true, when the shaft A³ is raised clear of the stone by reverse rotation of the hand-wheel A⁷. 25 A number of the roughly-formed file-blanks are then secured in the plate F, and the latter is placed within the frame F', and locked therein by means of the latch device f³f⁴. Figs. 2, 3, and 4 show the plates and blanks in place, the 30 frame F hanging in a vertical position on the pivot-bolt F¹⁸, and the screw F⁵ being at the extreme upward point of its movement. The grindstone having been set by means of its sliding bearings D' D' in the proper position 35 for acting upon the blanks during the vertical reciprocation of the frame F', and the rollers P P having been adjusted so as to bear against the back of the frame, power is applied to the belts upon the pulleys C, G', and G². As is 40 indicated by the arrows, Fig. 2, the belts upon the loose pulleys G' and G² are running in opposite directions, and, it being desired to cause the descent of the screw F⁵, the belt-shifters E⁸E⁸ are moved by hand, so as to shift 45 the belt from the loose pulley G² onto the fast pulley G, the other belt-shifters E⁹E⁹ remaining stationary. The rotation of the pulley G and shaft H in the direction of the arrow upon G² causes the nut bevel-gear F⁶ to turn to 50 the left, (or in a direction opposite to the hands of a watch,) and thus forces the screw F⁵ and cross-head F³ downward. When the screw F⁵ approaches the extremity of its downward movement, the tap-pin F⁸ strikes the horizontal 55 arm of the bell-crank E', depressing it, and, through the connecting-rod E⁵ and bar E⁶, moving the belt-shifters E⁸E⁸ onto the central or fast pulley G. As has been before explained, this movement pushes the belt-shifters E⁸E⁸ onto the 60 loose pulley G², thus reversing the motion of the fast pulley G, causing the ascent of the screw F⁵ and cross-head F³. When the screw F⁵ approaches the end of its upward movement, as indicated in Fig. 3, the tap-pin F¹² strikes the 65 horizontal arm of the bell-crank E, raising it and throwing the belt-shifters E⁸E⁸ onto the

fast pulley G. This movement pushes the belt-shifters E⁸E⁸ onto the loose pulley G', and the motion of the fast pulley is again reversed, so as to cause the descent of the screw. By 70 adjusting the tap-pins at different points upon the rod F⁹ the stroke of the screw F⁵ can be varied in length to any desired extent. The frame F' is by these movements of the screw F⁵ and cross-head F³ caused to reciprocate vertically in a plane tangential to the periphery of the grindstone C, and the pressure of the rollers P P against the back of the frame forces the file-blanks f into close contact with the rapidly-revolving stone. As has before 80 been explained, the stone itself has a lateral reciprocating motion caused by the pin D³ and cam-slot D², and the grinding is effected by these combined movements of vertical and horizontal reciprocation. This method not 85 only prevents the formation of lines and ridges in the file-blanks from inequalities in the grinding-surface, but obviates the uneven wearing away of the stone itself. The arrangement of the blanks upon the removable plate F permits the operator to examine them at any moment by tilting the plate backward, or even to remove the plate and insert another containing new blanks without stopping the machine. 90

The advantages of the various adjusting devices need not be particularized, as they will be obvious to one skilled in the use of such machinery, and their several modes of operation have been fully explained above. 95

I claim—

1. The combination, with the grinding device, of a blank-holder and a reciprocating frame adapted to receive and secure said holder, but open at the back (or side which is 105 farthest from the grinding device) to permit the insertion and removal of the blank-holder through the frame, substantially as set forth.

2. The combination, with the reciprocating frame and its removable blank-holder, of the 110 rollers P, adapted to bear against said frame adjacent to, but clear of the blank-holder, substantially as set forth.

3. The combination of the sliding pillow-blocks of the grindstone-shaft with the screw-connections O O' and the hand-wheel shaft m, said screw-connections and hand-wheel shaft being provided with bevel-gears separately adjustable thereon, whereby said pillow-blocks can be jointly as well as separately adjusted 120 by means of said hand-wheel shaft. 115

4. The combination of the sliding carriages Q of the bearing-rolls with the screw-rods P' and hand-wheel shaft m, said screw-connections and shaft being provided with bevel-gears separately adjustable thereon, whereby 125 said carriages can be jointly as well as separately adjusted by said shaft.

ALFRED WEED.
